RIBBON CARTRIDGE

Ernst Peter Hess, Castro Valley, Calif., assignor to
Xerox Corporation, Stamford, Conn.

Filed Feb. 15, 1973, Ser. No. 332,940

Term of patent 14 years

Int. Cl. D18—01

U.S. Cl. D64—11 A

FIG. 1

FIG. 3

FIG. 2

FIG. 4

FIG. 5

FIG. 6

FIG. 7

FIG. 1 is a perspective view of a ribbon cartridge showing my new design;

FIG. 2 is a top plan view thereof;

FIG. 3 is an elevational view taken from one side thereof;

FIG. 4 is a bottom plan view thereof;

FIG. 5 is an elevational view taken from the side opposite of that shown in FIG. 3;

FIG. 6 is an end elevational view thereof; and

FIG. 7 is an end elevational view taken from the end opposite of that shown in FIG. 6.

I claim:

The ornamental design for a ribbon cartridge, as shown.
